WAISTBAND CONSTRUCTION

Isadore J. Elman, Cazenovia, N. Y.

Application February 15, 1951, Serial No. 211,129

1 Claim. (Cl. 2—236)

1 This invention relates to a waistband construction, and more particularly to a construction in which the waistband lining and adjacent garment cloth are secured without resort to unsightly or blind stitching.

In garment waistband constructions, there is generally provided a buckram backing or stiffening strip and lining material which, together with the body garment material, substantially enclose such stiffening strip, all for the purpose of providing the necessary waistband stiffness. It is desirable that such construction, which gives body or stiffness to the garment material around the waistband, be affixed to such garment material by means invisible from the outward face of the garment. Resort has been made to blind stitching, where the body garment material is continuous, and where a separate waistband strip is attached to the body garment material, attempt has been made to lay the stitching in the seam therebetween or immediately adjacent thereto. The latter constructions require unusual care in the placing of the stitches, resulting in a slow operation and time-consuming care to prevent the production of irregular or unsightly appearing garments.

It is an object of the present invention to eliminate the need for such stitching completely from the outside face of the garment through utilization of a bonding construction, rapid in operation and requiring little skill.

A further object of the invention is the provision of a waistband construction in which a bonding means is employed for securing the backings construction to the body garment over a relatively broad area and along substantially the entire waistband length.

Still a further object of the invention is the utilization of bonding means in the form of thermo heat-setting plastic for the purpose of securing the waistband stiffening and lining construction to the body garment, whereby such elements may be permanently secured by the application of heat.

A further object of the invention is the provision of a construction readily adaptable to waistband constructions embodying continuous or separate waistbands, as well as various lining arrangements, the constructions being permanent, low cost, and providing a pleasing outward and internal appearance.

The above and other novel features of the invention will appear more fully hereinafter from the following detailed description when taken in conjunction with the accompanying drawings. It

is expressly understood that the drawings are employed for purposes of illustration only and are not designed as a definition of the limits of the invention, reference being had for this purpose to the appended claim.

In the drawings, in which like reference characters indicate like parts:

Figure 1 is a side elevation showing a pair of trousers, to which the invention may be applied;

Figure 2 is a sectional view taken substantially on the line 2—2 of Figure 1, of the construction prior to the application of heat in the bonding operation;

Figure 3 is a section taken substantially on the line 2—2 of Figure 1, showing the waistband construction in its completed form;

Figure 4 is a modified form of the invention, parts being broken away and shown in section for illustrative purposes;

Figure 5 is a further adaptation of the invention, parts being broken away and shown in section; and

Figure 6 is a further application of the invention, parts being broken away and shown in section.

In Figures 1, 2, and 3, there is shown a waistband construction which may be adapted to a pair of trousers or other garment having a waistband construction similar thereto. As shown, there is provided a waistband stiffening strip 10 which may be in the form of a strip of buckram backing or the like, preferably felted on the inside face, to which is stitched at its upper edge as at 12 the waistband strip 13 of the body garment material 14 and a facing or lining material 16, referred to as a curtain. In the arrangement shown, the facing or lining is formed of two strips of material 18 and 20, which may be twill or the like, stitched together as at 22 and to the stiffening strip 10 adjacent the lower edge thereof. Where the facing or lining is formed of double strips in this manner, it is referred to as a double curtain lining construction. The body garment material in the form shown comprises a separate waistband strip 13 stitched as at 26 to the main body garment 28 proper.

It has heretofore been common practice in a construction of the type described, wherein the body garment material is provided with a waistband strip, to stitch the lower marginal edge 30 of the stiffening strip 10 to the waistband strip either by stitching placed closely adjacent to the stitching 26 and running parallel therewith, or stitching in the seam 26, such stitching coinciding with the seam stitching so as to be substantially

hidden to all intents and purposes. In order to avoid the necessity for such stitching, which often appears unsightly, where absolute parallelism is not maintained, there is provided in accordance with the invention a strip of thermo heat-setting plastic 32, which may be readily placed in position by tucking an edge thereof between the lower marginal edge 30 of the buckram backing strip and the depending fold of facing or lining material 20. The strip of plastic is of a width slightly less than that of the depending portion of the lining material, so as to avoid having any portion thereof exposed. Upon positioning such strip in the manner described, the depending lining portion is pressed as by a hot iron 34 against the body garment proper, which is supported upon a yielding ironing buck. The heat and pressure fuse the plastic strip, causing the opposed surfaces thereof to soften and flow into the adjacent fabric surfaces, the result being to provide a bonding between the body garment material proper and the depending trim strip through the agency of such heat-setting plastic. The thermo heat-setting plastic thereby affords a broad strip area of bonding between the adjacent fabrics, providing high strength. At the same time, there is created a neat appearing garment free from the stitching operation heretofore referred to.

The thermo heat-setting plastic may consist of a thin strip of vinyl, independently placed between the fabrics in the manner described, or may constitute a layer strip bonded to the lining material prior to assemblage of the garment construction as shown in Figure 2. It may comprise a carrier strip of cloth, such as 20-square print cloth having the heat-setting plastic on opposite sides. In any event, the plastic is set by heat, which may be of the order of 375° F., and forms the bond between the lining and garment materials upon the application of heat.

The plastic chosen should have characteristics such that it may be heat set by a hot iron in the manner described, and be resistant to the usual cleaning fluids to which garments are subjected. It will be at once appreciated that each time a garment constructed in the manner described is subjected to a pressing operation, the bond between such plastic strip and the adjacent materials will be enhanced, and that by such an arrangement, the adjacent materials are permanently secured in an improved manner.

The invention is applicable to variations in waistband constructions, as, for example, illustrated in Figures 4, 5, and 6. In Figure 4, there is shown the usual buckram strip 40 to which is secured the body garment material 42, and facing or double curtain composed of strips 44 and 46, the upper strip and the garment material being stitched to the upper edge of the buckram strip as at 48. The strips 44 and 46 are stitched together as at 50, and stitched to the buckram strip adjacent its lower edge. A strip of thermo heat-setting plastic 52 is positioned between the strip 46 and by application of heat and pressure, caused to bond the garment material 42 to the strip 46. In the arrangement shown, the body garment material is continuous, there being eliminated the waistband strip, so that by such construction, the blind stitching heretofore referred to as utilized to secure the lining to the body garment is dispensed with.

In Figure 5, the lining strip 54 comprises a single strip, referred to as a single curtain, and such strip is secured as at 56 and 58 to the buck-

ram stiffening strip 59. In the arrangement shown, the folded portion 60 of the lining strip 54 is bonded to the garment material 62 as by the thermo heat-setting plastic strip 64. The construction of Figure 6 differs from Figure 5 in that the body garment material 66 is provided with a waistband strip 68 of the same material, and the lining strip 69 is similarly bonded to the material 66 by a strip of thermo heat-setting plastic 70.

While the stiffening element of buckram has been described as common practice, it will be understood that any strip of material having strength in the direction around the waistband 15 may be used. Where the body garment material may serve the additional purpose of providing waistband stiffness or strength, such strip of buckram or other material may be eliminated, in which case the lining strip or curtain will be secured to the upper edge of the body garment, substantially in the manner illustrated, but without the buckram element, and the lower fold secured to the body garment material by heat-setting thermo plastic in the manner described. 20 Such a construction may be efficacious where a separate waistband strip of the body garment material is employed as in Figures 1 to 3, it being understood that where such separate strip is used, greatest strength is exhibited in a direction 25 around the waistband.

The various constructions illustrated serve to illustrate the adaptability of the bonding construction, utilized to secure the lower edge portion of the stiffening and lining assemblage to the body garment without recourse to the unsightly stitching, or blind stitching herein referred to.

The construction is one which provides increased strength, eliminating stitching which localizes stresses, with a tendency to rupture the cloth or rip the seams upon the occurrence of severe stresses. Where the bonding strip is secured to the lining strip in advance of the assembling, the only operation required to effect the result described is that of applying heat and pressure, operations which may be generally effected in any event.

The use of the bonding means described, when applied in a manner so as to extend substantially to the edge of the lower fold thereof, serves to hold the lining flat against and in bonded engagement with the body garment, eliminating any depending fold portion which might otherwise be free to curl inwardly and upwardly away from the body garment, a condition occurring in presently known common constructions herein referred to, embodying the stitching eliminated by the present invention.

It will appear to those skilled in the art that the existence of pockets and the like which may be secured at their upper end in the waistband construction will generally be secured to the curtain where lying between the curtain and the body garment by the heat-setting plastic bonding strip, and that by such arrangement, the pocket structure will hang from the waistband assemblage rather than a combination thereof and the body garment material.

While several embodiments of the invention have been illustrated and described, it is to be understood that the invention is not limited thereto. As various changes in the construction and arrangement may be made without departing from the spirit of the invention, as will be apparent to those skilled in the art, reference will

be had to the appended claim for a definition of the limits of the invention.

What is claimed is:

A waistband construction comprising a stiffening strip of buckram, body garment fabric secured to the stiffening strip along the upper marginal edge thereof on the inside face of the buckram, said garment fabric depending from the upper edge of said stiffening strip and over the outside face thereof and below, lining fabric overlying the inside face of said buckram strip and having folded-over upper and lower edges forming upper and lower folds, the upper folded over edge of the lining being stitched to said stiffening strip through the upper marginal edge of the body garment fabric along the upper edge of said stiffening strip and closely adjacent the upper fold, the lower folded over edge depending substantially below the lower edge of said stiffening strip, the marginal edge of the lower folded edge being secured by stitches to the lower edge portion of said strip said stitches being spaced from the lower fold, and thermo plastic heat-setting material in strip form having its lower edge portion interposed between said garment fabric and the

10

20

25

lining fabric, and disposed with its upper edge portion adjacent said lower edge stitches, and with a substantial portion thereof below the lower edge of said stiffening strip, said heat-setting material being bonded over the major portion of its width between said garment fabric and said lining fabric, and being of a width substantially equal to the distance between the edge of said depending fold and said lower edge stitches.
